UNITED STATES PATENT OFFICE.

FRANZ ANTON HUBBUCH, OF STRASBURG, GERMANY.

MACHINE FOR GRINDING GLASS ARTICLES.

SPECIFICATION forming part of Letters Patent No. 665,786, dated January 8, 1901.

Application filed December 24, 1898. Serial No. 700,239. (No model.)

To all whom it may concern:

Be it known that I, FRANZ ANTON HUBBUCH, a resident of Strasburg, Alsace, Germany, have invented certain new and useful Improvements in Machines for Grinding Glass Articles, of which the following is a specification.

This invention relates to the automatic machine for grinding hollow glass objects described and shown in my application for Letters Patent filed December 31, 1897, Serial No. 664,928; and the objects of my present invention are to improve the prior machine, to extend its usefulness, and to effect scale-like and helical or undulatory grinding.

To accomplish these objects, my invention consists in the features of construction and in the combination or arrangement of parts hereinafter described and claimed, reference being made to the accompanying drawings, in which—

Figure 1 is a vertical sectional side view of a portion of my improved machine. Fig. 2 is a top plan view. Fig. 3 is a transverse section on the line C D, Fig. 1. Fig. 4 is a detail sectional view on the line E F, Fig. 3. Fig. 5 is a detail side view of the hook and pin for holding the sliding head retracted. Fig. 6 is a broken vertical sectional view showing a modified form of machine. Fig. 7 is a detail broken side view of a part of the modified sliding head. Fig. 8 is a top plan view of the parts shown in Fig. 6. Fig. 9 is a sectional view taken on the line E F, Fig. 6, showing the rack-bar lowered. Fig. 10 is a similar view showing the rack-bar raised. Figs. 11 and 12 are detail views of parts of the spindle-turning means, hereinafter explained; and Fig. 13 is a sectional view on the line G H, Fig. 1.

In order to enable those skilled in the art to make and use my invention, I will now describe the same in detail, referring first to Sheet 1 of the drawings, wherein the figures show a machine for executing scale-like grinding, where four crowns or ranges of twenty-four cuts or grindings each are to be produced upon the glass. The cutting or grinding is started at the crown or range which lies nearest the base of the glass.

The device for mounting the glass upon the machine is the same as that employed in the original machine, and it is only the method

of engaging the blank for obtaining the longitudinal movement and rotary movement of the glass which has been modified.

55

The hollow glass article or object to be ground is held by suitable chuck devices M, J, and D, the latter being driven by a chuck-spindle *u*, which is intermittently rotated in the sliding head B' B B², the latter being moved longitudinally on the support W under the grinding-disk or emery-wheel S. The head B' B B², according to this improved arrangement, is not placed in connection with the spindle; but, on the contrary, a weight suspended from the string or rope V, Fig. 1, tends to move the said head in the direction of the arrow—that is to say, toward the machine-frame. This movement is regulated by a stepped ring 1, bearing against the stop X. 70 To the stepped ring a ratchet-wheel 2 is rigidly connected, which is adapted to turn with said ring upon the piece W and in the present case is provided with ninety-six teeth. If now, in view of the engaging method referred 75 to, the stepped ring is turned in the direction in which the hand of a clock travels, (see Fig. 3,) the stop X drops from the step I upon the step II, and the glass is by the action of the weight displaced longitudinally to the extent of the height of the step, so that the emery-wheel engages with another part of the surface of the glass.

The operation of rotating the object to be ground is more difficult during the period of 85 working and especially if a crown or range has been ground and the subsequent crown or range has to be placed exactly central to the preceding crown or range. In order to illustrate this arrangement and operation, 90 Fig. 3 represents the position of the engaging mechanism at the commencement of the operation. With the eccentric-shaft Q, Fig. 2, an engaging shaft 3 is so connected that the same, under the action of the eccentric 23 and 95 of the coupling-lever 24, is compelled to execute an oscillating movement. This movement is by the aid of the cam transmitted to the lever 5 and causes the same to turn through an angle α at each revolution of the 100 shaft Q. This rotation is on its part transmitted to the shaft 6, which is provided with a lever 7. The latter is connected by means of the connecting-rod 8 to the sliding piece 9,

to which the pawl 10 is pivotally secured. The counterweight 11 has the effect of keeping the pawl in constant engagement with the ratchet-wheel T. The engaging gear is so adjusted that as the stone is lifted the shaft 6 so rotates under the action of an eccentric mounted on the shaft Q that the sliding piece 9 is lifted and that the ratchet-wheel T is moved to the extent of two teeth. For reasons which will be referred to later on the ratchet-wheel has double as many teeth as scales are required to be produced on one crown upon the periphery of the glass. In order that with this engaging mechanism also 10 the stepped ring I may be placed in connection, the shaft 6 is further provided with a short lever 12, on which a pawl 13 is arranged, which is adapted to engage with the ratchet-wheel 2. Now during the period in which the 15 pawl 10 causes the ratchet-wheel T to move to the extent of two teeth the pawl 13 moves the ratchet-wheel 2 to the extent of one tooth. Consequently when the forty-eight teeth of the ratchet-wheel T have been moved—in 20 other words, when the said wheel has completed one revolution—then also twenty-four teeth of the ratchet-wheel 2 have been moved, or, in other words, the latter has turned through an angle of ninety degrees, and if 25 then a further engaging operation commences the stop X drops off the step I, so that as the ratchet-wheel 2 further rotates the said stop then slides upon the step II. After 30 this operation a new crown or range of scales can be started. As this crown must be displaced to the extent of one-half division relatively to the preceding crown or range, I provide in the neighborhood of the shaft Q a further ratchet-wheel 14, having half as many 35 teeth as the ratchet-wheel T, and with the teeth of which a pawl 15, fixed to the shaft 3, is adapted to gear, whereby the motion of the ratchet-gear is stopped. At each revolution of Q this ratchet-wheel 14, always 40 45 at the moment when the eccentric 23 rotates, the glass is moved forward to the extent of one tooth—that is to say, to the extent of one twenty-fourth of its periphery—so that the pawl 15 in descending always engages between two teeth. The twenty-fourth—that 50 is to say, the last—space between the teeth is slightly lower than the others, (see Fig. 4,) and after the twenty-fourth surface has been 55 adjusted the pawl 15 descends deeper into the ratchet-wheel 14. Thus the whole engaging mechanism is placed lower and the pawl 10 has slid down along three teeth. If then after one revolution the glass is shifted in the manner above described to the extent of the 60 height of one step, the lever 24, and consequently also the pawl 15 and the whole stop-work, must now turn through the angle β and α , and this movement is sufficient for causing the ratchet-wheel T to be rotated to the extent of three teeth by the aid of the pawl 10. These three teeth correspond to the whole and one-half division of the crown of scales, and

the second crown lies exactly in the middle between the first. The pawl 10 in the further operation always shifts two teeth, and the whole second crown is evenly displaced relatively to the first. When the second crown has likewise been ground ready, the ratchet-wheel 14 has again completed one revolution, and on the stop X falling upon the stop III the pawl is again engaged with the lower tooth-clearing and the ratchet-wheel T is again shifted to the extent of three teeth, so that now also the third crown is displaced relatively to the second to the extent of one-half scale.

When all four crowns or ranges are ready and the machine has been thrown out of grasp, then by means of the handle 19 the head B' B B² is pulled forward and moved into its position of rest by causing the hook 20 connected therewith to fall into the catch 21, arranged on the adjusting-ring N.

In conformity with the explanations the construction may also be such that five or more ranges of scales may be arranged upon the glass by simply providing a different number of steps upon the ring.

Sheet II shows a machine for producing an entirely new kind of grinding—the so-called "helix grinding." By this apparatus helical grooves are intended to be ground in the glass, as shown in Fig. 8. The engaging operation differs from that hereinbefore described, inasmuch as during the period in which the emery-wheel attacks the glass the latter simultaneously executes a longitudinal and a rotary movement. The longitudinal movement is obtained in the same manner as in the case of the original machine, whereas the simultaneous rotary movement is produced by a slotted piece or race 1^a, which is screwed to the ring N, and thus to the front portion of the support W. The oblique slot in this race has a small roller 2^a, which is so screwed to the rack-bar 3^a as to be rotatable thereon, while the latter gears with a wheel 4^a, having part of its periphery provided with teeth and being adapted to freely rotate about the guide u when the rack-bar is being moved downward. Fig. 10 represents the rack-bar in its lowest position, which it occupies at the commencement of a grinding operation. Fig. 9 represents the rack-bar in its highest position, which it occupies when a helical facet has been ground. As the rack-bar 3^a passes from the one position to the other, which takes place as the head B' B B² is moved in the direction of the arrow, the engaging cone 5^a, fixed to the wheel 4^a, carries the ratchet-wheel 6^a along with it in the direction in which the hands of a clock travel, Fig. 9, and the glass is through an angle α , seeing that the ratchet-wheel 6^a is connected to the spindle u by a wedge 7^a. This rotary movement coincides with the longitudinal movement and the glass is passed along underneath the emery-wheel while moving in a helical line of high pitch. In order to admit of a second facet of this

kind being ground, the emery-wheel, as in the case of the original machine, is at the end of the stroke lifted off the glass and starts running idle. Upon the same the small roller 2^a 5 must again participate in the compulsory movement within the slot of the race, and the glass would be again moved back to the exact extent as that through which it had been moved forward during the grinding period 10 in the direction in which a hand moves upon the dial of a clock—namely, through the angle α . As, however, the glass has to receive a new facet, this return movement must be smaller to the extent of one facet division 15 than the rotation executed during the grinding movement. The ratchet-wheel 6^a has just as many teeth as the glass is required to receive helical facets. If, therefore, the angle α comprises three teeth, then during the time 20 the emery-wheel runs idle the rotation of the glass may amount to two tooth divisions equal to the angle β . This reduced rotary motion is obtained in the following manner: The engaging cone 5^a, Figs. 7, 8, 9, 10, 11, 25 and 12, has a bolt 8^a acted upon by a spiral spring, which bolt is forced inward in the direction of its axis by means of the nose 9^a, fixed to the head-frame B' B², when, during the period in which the glass is acted 30 upon, the ratchet-wheel rotates. The nose 9^a is now so beveled and adjusted that the said bolt 8^a, during the return movement of the cone 5^a, is forced out in a radial direction. The cone 5^a rotates and is passed out of 35 engagement with the ratchet-wheel 6^a, so that now the glass no longer participates in the rotary motion until the wheel 6^a has turned through the angle α and β . Finally the nose 9^a permits of the bolt 8^a dropping in under the 40 influence of the counterweight 10^a and the pawl again engages with a clearing, so that a fresh engaging operation through the angle α can be effected. The nose 9^a is exactly adjusted, and, together with a small plate 45 provided with slotted holes, it forms one piece, which is screwed to the frame.

What I claim is—

1. In a machine for grinding hollow glass objects, the combination of a support, a sliding head on said support, a stepped ring carried by the sliding head, a fixed stop coöperating with said ring for controlling the sliding movement of the head, a chuck-spindle mounted on the sliding head, and means for intermittently turning the spindle, substantially as described. 50

2. In a machine for grinding hollow glass objects, the combination of a support, a longitudinally-movable head mounted on said support, means for imparting a step-by-step longitudinal movement to the head in one direction, a chuck-spindle mounted in the sliding head, and means for intermittently turning the spindle. 60

3. In a machine for grinding hollow glass objects, the combination of a support, a longitudinally-movable head mounted on said

support, a stepped ring rotatably mounted on the head, a fixed stop coöperating with said stepped ring for controlling the sliding movement of the head, a chuck-spindle carried by the said head, means for turning said spindle intermittently, and means operated by the spindle - turning means for rotating the stepped ring at intervals, substantially as described. 70

4. In a machine for grinding hollow glass objects, the combination of a support, a longitudinally-movable head mounted on said support, a stepped ring rotatably mounted on the head, a fixed stop coöperating with the stepped ring for controlling the sliding movement of the head, a chuck-spindle carried by the head, means for turning said spindle intermittently, and a cam and intermediate 85 mechanism for operating the spindle-turning means. 80

5. In a machine for grinding hollow glass objects, the combination of a support, a longitudinally-movable head mounted on said support, a stepped ring rotatably mounted on the head, a fixed stop coöperating with said stepped ring for controlling the sliding movement of the head, a ratchet-wheel on the stepped ring, a chuck-spindle carried by the head, means for rotating the chuck-spindle intermittently, and devices operated by the spindle-turning means for engaging the ratchet-wheel on the stepped ring to rotate the latter at intervals, substantially as described. 90

6. In a machine for grinding glass objects, the combination of a support, a longitudinally - movable head mounted on said support, a stepped ring rotatably mounted on the head, a fixed stop coöperating with said ring for controlling the sliding movement of the head, a ratchet-wheel carried by the ring, a chuck - spindle mounted on the head, a ratchet-wheel fixed to the spindle, and mechanism operated from a common shaft for rotating both of said ratchet-wheels, substantially as described. 105

7. In a machine for grinding glass objects, the combination of a support, a longitudinally - movable head mounted on said support, a stepped ring rotatably mounted on the head, a fixed stop coöperating with said ring for controlling the sliding movement of the head, a chuck - spindle mounted on the head, a ratchet-wheel carried by the spindle, 115 engaging means for the ratchet-wheel, a rotating cam, and devices operated by said cam for imparting an intermittent movement to the ratchet-wheel-engaging means, substantially as described. 120

8. In a machine for grinding glass objects, the combination of a support, a longitudinally - movable head mounted on said support, a chuck-spindle carried by the head, a toothed wheel fixed to the spindle, a rack-bar 130 engaging the toothed wheel for turning the latter, and means for operating the rack-bar, substantially as described. 125

9. In a machine for grinding glass objects,

the combination of a support, a longitudinally-movable head mounted on said support, a chuck-spindle carried by the head, a toothed wheel fixed to the spindle, a reciprocating bar arranged adjacent to said toothed wheel, means carried by the bar for engaging the toothed wheel, and mechanism for moving the bar up and down to cause the spindle to turn, substantially as described.

10. In a machine for grinding glass objects, the combination of a support, a longitudinally-movable head mounted to slide on said support, a stepped ring carried by the head, a fixed stop coöperating with said ring to con-

trol the longitudinal movement of the head, 15 a chuck-spindle carried by the head, a rotary shaft Q, carrying a cam, a rock-shaft 3, operated by said cam, and means operated by the rock-shaft for rotating the chuck-spindle and the stepped ring intermittently, substantially as described. 20

In testimony whereof I have hereunto set my hand, in presence of two subscribing witnesses, this 5th day of December, 1898.

FRANZ ANTON HUBEUCH.
